ATTORNEY.

UNITED STATES PATENT OFFICE.

ALBERT B. HOLLEY AND JOHN A. GAVIN, OF VIRGINIA, MINNESOTA, ASSIGNEES, BY
DIRECT AND MESNE ASSIGNMENTS, TO SAID ALBERT B. HOLLEY.

ATTACHMENT FOR RADIATORS.

Application filed June 30, 1922. Serial No. 571,894.

To all whom it may concern:

Be it known that we, ALBERT B. HOLLEY and JOHN A. GAVIN, citizens of the United States of America, residing at Virginia, in the county of St. Louis and State of Minnesota, have invented certain new and useful Improvements in Attachments for Radiators, of which the following is a specification.

- 10 Our present invention relates generally to attachments for radiators, and more particularly to bushings whereby without the use of valves, required quantities of steam may be furnished steam radiators, our object being the provision of a device of this nature by the use of which hot water and other house heating radiators may be converted to the use of steam and the bushing regulated when fitted to the radiator so as 20 to supply the desired and proper amount of steam without the use of supply regulating valves and in such manner as to prevent unwarranted tampering with the steam supply.
- 25 The invention is especially applicable in apartment houses and the like for these reasons and is not only inexpensive in first cost but is practically without expense as far as upkeep is concerned and is peculiarly and uniformly effective for the intended purposes.

In the accompanying drawing which illustrates our present invention and forms a part of this specification,

30 Figure 1 is an end view of a steam radiator showing our improved bushing applied thereto,

Figure 2 is a vertical longitudinal section therethrough,

35 Figure 3 is a vertical longitudinal section through a hot water radiator showing our invention adapted thereto,

Figure 4 is an end view of the bushing looking at the inner end thereof,

40 Figure 5 is an enlarged end view looking at the outer end of the bushing, and

Figure 6 is a central longitudinal section through the bushing shown in Figure 5.

45 Referring now to these figures our invention proposes a bushing which may be applied to either a steam radiator such as shown at 10 in Figures 1 and 2 or a hot water radiator such as shown at 11 in Figure 3, the bushing being connected in Fig-

ures 1 and 2 to the lower portion of the end 55 coil while in the case of the water radiator of Figure 3 is connected to the upper portion of the end coil, and is not only adapted to convert the water radiator of Figure 3 into a steam radiator but is in each instance 60 adapted to regulate the amount of entering steam exactly to the requirements without danger of unwarranted tampering after the bushing is in place although capable of removing should a change be thereafter required.

In presenting this metering radiator bushing capable of avoiding the necessity of supply regulating valves, our invention proposes a bushing having a generally cylindrical chambered or hollow body 12, provided at its outer end with an external wrench engaging surface as for instance in the nature of a polygonal flange 13 and provided with external threads 14 adjacent to 75 the flange to engage threads within the bushing receiving bore of a radiator.

The chamber of the bushing is best seen at 15 in Figure 6, it being noted that the outer end of the bushing has an internally 80 threaded supply pipe receiving bore 16 extending centrally therethrough and in communication with the chamber 15 and that the inner portion or end of the bushing has either a single opening or an annular series 85 of openings radiating from the inner portion of the chamber and thus located in that portion of the bushing which when properly fixed within a radiator 10, 11, is disposed within its steam receiving space of the 90 radiator.

Where an annular series of openings 17, 18, 19, 20, 21 and 22, are employed, they are graduated as to cross section around the bushing, each leading from the chamber of 95 the bushing and each being closed at its outer end by a small screw or other plug 23 so that it becomes apparent that it is simply necessary in every instance to determine the size of supply opening necessary 100 to bring about supply of the proper amount of steam to a radiator and remove the closure plug 23 of that particular opening or channel or the plugs of two or more channels the combined areas of which are 105 necessary to furnish the desired amount of steam.

In order that the selected open channel

may be directed within the radiator as desired, it is preferable that the series of openings or channels above mentioned, having corresponding series numbers as indicated at 5 24 upon the outer end of the bushing and around its supply pipe receiving bore whereby when the bushing is inserted in a radiator it may be turned until the selected open 10 channel is directed up or down within the radiator or in whatever other direction may be desired.

It is obvious that when our improved bushing is once inserted, the supply of steam is thereby regulated without danger of 15 change except by removal of the bushing, so that unwarranted tampering is prevented and the necessity for supply controlling valves is avoided. Our invention is not only inexpensive as compared to valves and 20 the like in its first cost, but is unlike valves practically free of all upkeep expense and will be uniformly effective for the purposes intended.

We claim:

- 25 1. A radiator bushing comprising a chambered body flanged at one end and externally threaded adjacent to said flange to screw within a receiving aperture of a radiator, said body having a threaded supply pipe 30 receiving bore centrally of its flanged end opening into its chamber, and having at its opposite ends a series of graduated openings of varying sizes radiating from its chamber and each provided with a removable closure, said bushing having at its first 35 mentioned end a series of distinguishing numerals opposite and corresponding to the openings of said series of openings as described.
- 40 2. A radiator bushing comprising a chambered body flanged at one end and externally threaded adjacent to said flange to screw within a receiving aperture of a radiator, said body having a threaded supply pipe 45 receiving bore centrally of its flanged end opening into its chamber, and having at its opposite ends a series of graduated openings of varying sizes radiating from its

chamber and each provided with a removable closure.

3. A radiator bushing comprising a chambered body having wrench engaging means at one end and having an externally threaded portion, said body having a threaded bore through said end opening into its chamber and having a series of apertures of graduated cross section through its opposite end, opening into its chamber, and plugs forming detachable closures for said apertures.

4. A bushing comprising a hollow body externally threaded to screw into a radiator opening, having at one end a threaded supply pipe receiving bore, and having at its opposite end a series of radiator supply 65 apertures with means to regulate the effective area of and supply through, said apertures.

5. A radiator bushing comprising a hollow externally threaded body having a 70 threaded supply pipe receiving bore at its outer end and having at its inner end a series of radiator supply apertures of varying cross sections, each aperture having a removable closure for the purpose described.

6. A supply bushing for steam radiators, comprising a hollow externally threaded body adapted to be screwed into a radiator coil and having a threaded supply pipe receiving bore at its outer end, said bushing 80 having a radiator supply aperture of predetermined area substantially reduced with respect to its body bore and opening through the wall of its inner portion in open communication with the hollow of the body, 85 said aperture forming a steam nozzle disposed so that the inflow of steam through the bushing in use may be forcibly directed upwardly into a radiator coil, the inner end of the bushing being closed so as to prevent inflow to a radiator except through said nozzle forming aperture.

In testimony whereof we have affixed our signatures.

ALBERT B. HOLLEY.
JOHN A. GAVIN.
